(57) **CLAIM**

The ornamental design for a wine glass, as shown and described.

DESCRIPTION

FIG. 1 is a perspective view of a wine glass in accordance with the present design;

FIG. 2 is a side view of the wine glass of FIG. 1;

FIG. 3 is a top view of the wine glass of FIG. 1; and,

FIG. 4 is a bottom view of the wine glass of FIG. 1.

The dash-dashed lines and the dot-dashed lines shown in the drawings illustrate portions of the wine glass and form no part of the claimed design.
